CURTAIN OR DRAPERY TIE-BACK

Filed April 24, 1944

UNITED STATES PATENT OFFICE

2,403,361

CURTAIN OR DRAPERY TIEBACK

John Hagen, Overland, Mo.

Application April 24, 1944, Serial No. 532,461

7 Claims. (Cl. 160—349)

1

The invention relates to curtain or drapery tie-backs or holders, and has for one of its objects, the purpose of providing tie-backs of an improved construction.

Another object of the invention is to construct the tie-back from light weight and substantial material.

A further object is to provide the tie-back of a baked clay product, which in addition to serving for curtain tie-back purposes, will also serve as a ceramic decoration to a curtain draped window.

A still further object is to provide a curtain tie-back with paralleling legs of a molded bifurcated construction.

With the foregoing and other objects in view which will appear as the description proceeds, my invention resides in the combination and arrangement of parts and in the details of construction hereinafter described and claimed, it being understood that changes may be made within the scope of what is claimed without departing from the spirit of the invention.

An embodiment of the invention is illustrated in the accompanying drawing, wherein:

Figure 1 is a perspective elevation of a curtained window, showing the application and use of this improved curtain tie-back.

Figure 2 is an enlarged inverted plan view of a pair of right and left members, used in assembling the tie-back.

Figure 3 is an enlarged vertical sectional elevation taken on the line 3—3 of Fig. 2.

Figure 4 is an enlarged plan view of the assembled tie-back.

Figure 5 is an enlarged front elevation of the tie-back.

Referring by numerals to the several figures of the accompanying drawing, 6 and 7 represent a pair of right and left legs, spaced from one another and each being curved at 8 on one end and having a flattened part 9 at each curved end, as shown in Fig. 2.

Each of the legs 6 and 7 has a deep longitudinal groove 10 thereby providing each leg with a pair of walls or bifurcated portions 11.

The legs 6 and 7 are preferably made of a molded clay product, such as potters clay as used in the fictile arts, and after being separately molded and sufficiently dried, are disposed parallel to each other with their flattened parts 9 in approximate abutment, and in this position, the parts 9 are treated with a solution of clay-slip for primarily securing the legs 6 and 7 together. After the clay-slip between the parts 9 has sufficiently dried, the secured together legs

2

6 and 7 are put in the kiln or oven to bake the clay-slip and the joined parts together.

After baking, the secured together legs 6 and 7 are then coated with a glazing solution by dipping

or other means, and if ornaments such as 12, as shown in Figs. 1, 4 and 5 are desired, they are glazed and primarily secured to one of the legs (in the instance shown, to the leg 6 to provide a left hand tie-back) by the glazed coating.

10 The ornaments 12 are clay molded and baked before being glazed.

The secured together legs 6 and 7 and the ornaments 12 thereon, are then baked or fired, and upon removal from the kiln the parts 6, 7

15 and 12 are firmly and substantially secured together and having a porcelain finish.

The inner surfaces of the grooves 10 of the legs 6 and 7 after the baking and glazing operations, are coated with shellac or analogous fast drying

20 material as shown at 13 in Fig. 3, to provide binding reinforcement to the legs and the walls 11 thereof, this addition to the construction, providing a light-weight and yet strong tie-back structure in ceramic utility decorations.

25 The shellac coating of the leg grooves 10 will cause a relatively thick body 14 to form at the bottom of the grooves, which when hardened, will provide a longitudinal stiffener to the legs in addition to the shellac reinforcement on the walls 11.

After the glazing operation a horizontally disposed resilient clasp 15 is cemented at 16 to the rear end of the leg 6 on the inner face thereof and a vertically disposed hanger 17 is secured to the outer surface of the leg 7 intermediate its length by cementing 18, as shown in Figs. 1, 4 and 5, and the hanger 17 extending above and below the leg 7.

The aforesaid description completes the construction of this improved curtain or drapery tie-back as representing a left-hand tie-back designated as 19, and as tie-backs are used in pairs, a right hand tie-back is made by securing the ornaments 12 and the clasp 15 on the leg 7

45 and the hanger 17 on the leg 6, as shown at 20 in Fig. 1, each tie-back when in use being disposed with the grooved faces of the legs lowermost.

In use, a draped curtain is engaged between the legs 6 and 7 of the tie-back, after the hanger 17 has been mounted on a hook 21 or the like on the frame or a wall surrounding the window, and for further securing the tie-back, the lower end 22 of the hanger may be engaged over a

55 projection or hook.

By making the legs of the tie-back hollow by the deep longitudinal grooves 10, and reinforcing the walls 11 of the grooves by a binding material, a strong and light weight porcelain or earthenware tie-back structure is provided, and the tie-back being ornamented in the manner as shown and described, a ceramic decoration which can readily be removed for cleaning by washing, is also provided.

It is obvious that changes may be made in the details and manner of construction within the scope of the appended claims, without departing from the spirit of the invention.

What I claim is:

1. A tie-back for a draped curtain comprising a pair of spaced paralleling legs joined at one end, and a resilient clasp for curtain engagement secured to one of said legs adjacent its free end.
2. A tie-back for a draped curtain comprising a pair of spaced paralleling legs joined at one end, and a resilient clasp secured to the free end of one of the legs for engaging and holding one side of the curtain.
3. A tie-back for a draped curtain comprising a pair of spaced paralleling legs joined at one end, a curtain engaging clasp secured to one

of said legs, and a securing hanger for the tie-back carried by the other leg.

4. An earthenware tie-back for a draped curtain comprising a pair of spaced paralleling legs each being bent at one end and joined at their bent ends, each of said legs having a deep longitudinal closed end groove formed therein.

5. An earthenware tie-back for a draped curtain comprising a pair of spaced paralleling legs each having a part joined to one another at one end, each of said legs having a deep inverted closed end groove formed therein and extending the approximate length thereof.

6. A tie-back of molded material for a draped curtain comprising a pair of spaced paralleling legs joined at one end, each leg having a deep longitudinal closed end groove for the reception and retention of a self hardening and binding reinforcement material.

7. A bifurcated curtain tie-back of molded material having a deep longitudinal groove in a branch thereof, for the reception and retention of a self hardening and binding reinforcement material.

JOHN HAGEN.
